GROTESQUE FISH-LIKE ORNAMENT

Charles J. Kurella, 158 John St., Whiting, Ind.

Filed Sept. 19, 1962, Ser. No. 71,765

Term of patent 14 years

(Cl. D29—23)

Fig. 1.

Fig. 2.

FIG. 3.

FIG. 4.

FIG. 5.

FIG. 1 is a side elevational view of a grotesque fish-like ornament showing my new design, the side opposite thereto being similar to that shown;

FIG. 2 is a top plan view;

FIG. 3 is an end elevational view looking from the left to right of FIG. 1;

FIG. 4 is an end elevational view looking from right to left of FIG. 1; and

FIG. 5 is a bottom plan view of FIG. 1.

I claim:

The ornamental design for a grotesque fish-like ornament, as shown and described.
